US00D894997S

(12) **United States Design Patent** (10) **Patent No.:** **US D894,997 S**
(45) **Date of Patent:** **** Sep. 1, 2020**

(54) **MONITOR**

(71) Applicant: **BLD Oriental Co., Ltd.**, Izumisano, Osaka (JP)

(72) Inventor: **Yasushi Ochi**, Osaka (JP)

(73) Assignee: **BLD Oriental Co., Ltd.**, Izumisano, Osaka

(**) Term: **15 Years**

(21) Appl. No.: **29/634,553**

(22) Filed: **Jan. 23, 2018**

(30) **Foreign Application Priority Data**

Jul. 25, 2017 (JP) 2017-016008

(51) **LOC (12) Cl.** **16-02**

(52) **U.S. Cl.**

USPC **D16/221**

(58) **Field of Classification Search**
